UNITED STATES PATENT OFFICE

160,594

WOMAN'S STOCKING OR SIMILAR ARTICLE

Otto W. Grummt, Philadelphia, Pa.

Application February 28, 1950, Serial No. 8,186

Term of patent 14 years

(Cl. D47—7)

To all whom it may concern:

Be it known that I, Otto W. Grummt, a citizen of the United States, residing at Philadelphia, in the county of Philadelphia and State of Pennsylvania, have invented a new, original, and ornamental Design for a Woman's Stocking or Similar Article, of which the following is a specification, reference being had to the accompanying drawing, forming part hereof, in which the figure is a side elevation of a woman's stocking embodying my design.

I claim:

The ornamental design for a woman's stocking or similar article, as shown.

OTTO W. GRUMMT.
